UNITED STATES PATENT OFFICE

MICHAEL J. MCRAE, OF SCRANTON, PENNSYLVANIA

FLIER CONSTRUCTION

Original application filed May 31, 1930, Serial No. 458,212. Divided and this application filed January 9, 1931. Serial No. 507,676.

This application is a division of my application Number 458,212, filed May 31, 1930, for flier constructions.

It is an object of this invention to provide an improved wooden flier block having a freely movable gripping member disposed therein and retained in position by a self mushrooming bushing member.

It is also an object of this invention to provide such an improved flier block in which the self mushrooming bushing is adapted for locking engagement with the flier block.

These and other desirable objects and advantages of the present invention will be described in the accompanying specification and illustrated in the drawing, certain preferred embodiments being shown by way of illustration only, for, since the underlying principles may be embodied in other specific mechanical devices, without departing from the spirit and scope of the present invention, it is not intended to be limited to the forms here shown except as such limitations are clearly imposed by the appended claims.

In the drawing like numerals refer to similar parts throughout the several views of which

Fig. 1 is an elevation of a bobbin mounted on a spindle and having a flier block and cap 30 together with an associated flier wire held in position by a flier cap;

Fig. 2 is an elevation of a novel flier cap showing means for retaining a plurality of flier wires;

Fig. 3 is a view similar to Fig. 2 showing means for retaining a single flier wire;

Fig. 4 is a vertical section of a wooden flier block having a centrally disposed spring for engagement with the spindle, the locking bushing being shown ready for assembling, and

Fig. 5 is a view similar to Fig. 4 showing the locking bushing in position.

Referring now to the drawing there is shown in Fig. 1 a bobbin, 1, mounted on a spindle, 20. The latter is tapered and at its upper portion is adapted to receive a flier block 30, having flier wire 23 mounted therein and held in position by means of an improved flier cap, 11.

In the modification which is the subject of the present application, the usual bobbin 1 is mounted on a spindle 20 of tapering cross section adapted to engage a wooden flier block 21. This latter is provided with the usual groove 22 for receiving the flier wire 23. The flier wire has depending arms 24 and thread engaging eyelets 25 as well as the usual central portion engaging the slot 22 in the flier block. A flier cap 11 configured to the shape of the block, is fitted over the block and the wires sprung into engagement with the slots 12 and/or 13. As above noted, a plurality of flier wires may be made use of, where desired, by the simple expedient of using the pair of double slots 12, rather than the pair of single slots 13. For easy manufacturing and to avoid duplication of parts, the two series of slots 12 and 13 may be formed in a single device, either set being used at will by the operator.

The novel flier cap and block assembly of the present invention is characterized by extremely low cost of manufacture, due to the fact that the wooden blocks may readily be formed by automatic machinery and the flier caps may be stamped or pressed out from sheet metal of suitable thickness.

Referring now to Figs. 4 and 5, there is shown a novel wooden block construction, which is adapted for use with the novel flier cap of my application No. 458,212, filed May 31, 1930, for flier constructions, of which the present application is a division, thus obviating the necessity of using mill nuts or other such locking devices. The construction shown comprises the usual wooden flier block 30 having the central groove 31 and central aperture 32. A bushing 33 of metal or other suitable material is forced into the block and engages the wood thereof permanently so as to serve as a retaining flange for the spring member 34, the latter, it will be appreciated, being adapted to engage a spindle member and permit the block to freely rotate thereabout. A bushing 35 having the usual central aperture of a diameter corresponding to that of member 33 is provided with a flange 36 of relatively square cross section and an associated depending flange 37 which is pro-

vided with an outwardly tapering section. The member 35 is adapted to fit into a seat 38 in the block 30 and be compressed or forced into position, against said seat, the section 37 mushrooming and digging into the body of member 30, as indicated at 39, thus locking member 35 firmly into place and retaining spring 34 in position. It will thus be seen that the central aperture block 30 together with the bushings 33 and 35 serve to retain the spring 34 in position and rotate freely thereabout. The device just described is particularly adapted for use with the improved flier cap of the present invention, and permits the use of cheap wooden construction in preference to a machined metal flier block construction.

A flier cap 11 having a plurality of apertures 12 and 13 oppositely disposed with respect to each other at the one edge thereof, and a central aperture adapted for engagement with the hub is slipped over the flier block. In operation, the flier block is inserted in the bushing of the bobbin and the assembly is then placed over and on a spindle. A flier wire having a central portion adapted to engage channel 31 and abutting thereagainst as a bearing surface is inserted in position, the flier cap is next lowered into position over the hub of the block. The arms of the flier wire are bent away from the central portion thereof which is in abutment against the block, until the said arms engage the slots 12 and/or 13 of the said caps, being held in position thereby, and serving to tense the flier wires in place.

It will now be appreciated that there has been provided a plurality of flier block constructions in which a unitary flier cap of sheet metal or other like construction and of suitable size and configuration is adapted to be used and thus permit the use of replaceable flier wires without requiring dismounting or removal of the flier blocks from their respective spindles.

In accordance with the provisions of the patent statutes, I have described the principles of operation of my invention, together with the device which I now consider to represent a preferred embodiment thereof; but I desire to have it understood that the device shown is only illustrative of the basic concept of the present invention, and that the said invention may be carried out by other means.

What is claimed is:

1. A flier including an apertured body portion having an annular wire-receiving groove, a movable spring member in the aperture adapted to grip a spindle, a fixed bushing in the body adapted to support the spring and a mushroom bushing opposite to said first bushing and cooperating therewith.

2. A flier including an apertured body portion having an annular wire-receiving groove, a movable spring member in the aperture

adapted to grip a spindle, a fixed bushing in the body adapted to support the spring and a mushroom bushing opposite to said first bushing and forced into said body.

3. A bushing for insertion into compressible flier bodies, comprising an annulus having a plurality of peripheral ridges, at least one of said ridges having a cutting edge. 70

4. A bushing for insertion into compressible flier bodies, comprising an annulus having a plurality of peripheral ridges, at least one of said ridges being displaced outwardly from the body of the bushing to form a cutting edged member. 75

5. A bushing for insertion into compressible flier bodies, comprising an annulus having a plurality of peripheral ridges, at least one of said ridges being so constituted and arranged as to present a cutting edge adapted to be forced into a flier body. 80

In testimony whereof I affix my signature. 85

MICHAEL J. McHALE.
